UNITED STATES PATENT OFFICE.

WILLIAM B. BALDWIN AND JOHN CURTIN, OF SOUTH MADISON, WISCONSIN.

MEANS FOR CONVERTING ROTARY INTO RECIPROCATING MOTION.

1,307,474.

Specification of Letters Patent. Patented June 24, 1919.

Application filed June 22, 1918. Serial No. 241,403.

To all whom it may concern:

Be it known that we, WILLIAM B. BALDWIN and JOHN CURTIN, citizens of the United States, residing at South Madison, 5 in the county of Dane and State of Wisconsin, have invented certain new and useful Improvements in Means for Converting Rotary into Reciprocating Motion, of which the following is a specification, reference being had to the accompanying drawings.

This invention relates to improved means for converting rotary into reciprocating motion, and has for its primary object to provide a very simple device which may be advantageously employed for the operation of engine pistons, saws, sickles, and in like instances, whereby a true rectilinear reciprocating movement may be transmitted at high speed.

It is another object of the invention to provide a device of the above character which when used in connection with a reciprocating engine eliminates the necessity of employing a cross head and guides therefor, 25 so that space may be economized in the installation of the engines, while at the same time, the free reciprocating movement of the piston without binding will be assured.

It is also a further general object of our 30 invention to materially simplify the construction and increase the efficiency of devices for the above purpose and thereby render the same strong and durable, and capable of manufacture at relatively small 35 cost.

With the above and other objects in view, the invention consists in the improved construction, combination and relative arrangement of the several parts as will be herein- 40 after more fully described, subsequently claimed and illustrated in the accompanying drawings in which similar reference characters designate corresponding parts throughout the several views, and wherein:—

45 Figure 1 is a side elevation, one of the side plates of the internal gear being removed;

Fig. 2 is a vertical sectional view;

Fig. 3 is a view similar to Fig. 1, showing the piston rod at the end of its stroke in one 50 direction; and

Fig. 4 is a side elevation showing the device operating a reciprocating saw.

Referring in detail to the drawings, 5 designates an annular internally toothed gear. The teeth 6 of this gear terminate

at one end of their ends in spaced relation to the edge of the gear to provide an annular track, indicated at 7, for a purpose which will be later explained.

The opposite sides of the annular gear 5 60 are closed by means of the side plates 8, and screws or bolts 9 are engaged through spaced openings in the outer edges of these plates and also through a fixed standard or support, whereby the internal gear may be rigidly secured in position.

A shaft 10 is rotatably mounted in the supporting frame or standard and in one of the side plates 8, said shaft being provided upon its outer end with a belt wheel or gear 11, through the medium of which rotation may be transmitted to said shaft or, if desired, in adapting the device to reciprocating engines, the shaft 10 may constitute the power shaft of the engine. Upon the shaft 75 10 within the annular gear 5, a crank arm 12 is fixed at one of its ends. An externally toothed gear 13 is loosely mounted upon the other end of this crank arm and has meshing engagement with the teeth 6 of the internal 80 gear. Upon this latter end of the crank arm at the outer side of the gear 13, an arm 14 is loosely engaged and extends radially upon the face of the gear. The outer end of this arm 14 is fixed to the gear face by the wrist 85 pin 15, in longitudinal alinement with the shaft 10. Upon this wrist pin, the end of a piston rod 16 or other element to which reciprocatory motion is to be transmitted, is loosely engaged. This rod extends through 90 a stuffing box indicated at 17, which is provided upon the rim of the annular gear 5.

The gear 13 is formed with an annular flange 18 at the side thereof from which the wrist pin 15 projects, and this flange is engaged upon the annular track 7 formed upon the inner face of the gear 5. This flange greatly strengthens the teeth of the gear 13 and affords a smooth, contact or rolling face which relieves the crank arm 14 of the 100 weight of the said gear.

In Fig. 1 of the drawings, we have shown the device as applied to a steam engine, and by comparing said figure with Fig. 3 of the drawings, it will be seen that in the rotation of the shaft 10, the small gear 13 tracks around the teeth of the larger internal gear, and the wrist pin 15 moves diametrically in a straight line across the interior of the internal gear as the gear 13 travels through its 110

circular path. Thus, a true reciprocating movement is imparted to the rod 16 and the piston fixed thereto so that there will be no binding engagement of the piston with the 5 walls of the engine cylinder. Thus, the necessity of providing cross heads and guides for the reciprocating piston will be entirely obviated, and the length of the engine 10 may be materially reduced. The weight also is appreciably lessened so that considerable economy may be realized in the installation of the engine.

In Fig. 4 of the drawings, we have shown our invention applied for the operation of a saw S. In such use, the rod 16' may be rigidly fixed to the end of the saw blade. It will also be apparent that the device can likewise be advantageously used in connection with grain mowers for the operation of 20 the sickle. The device can likewise be applied to many other analogous uses. The device may be driven at a very high speed without binding or derangement of its several parts and as the gear elements are entirely inclosed, grain, straw or other foreign matter cannot become entangled in the gear teeth. The small gear 13 is, of course, one-half the ratio of the large gear 5 and such ratio is maintained regardless of the 25 sizes in which the device may be constructed and whereby its speed is predetermined.

From the foregoing description, taken in connection with the accompanying drawings, the construction, manner of use and 30 several advantages of the device will be clearly and fully understood. By eliminating the use of a cross head and guides all friction is avoided, and the use of lubricating oil also economized. It is only necessary to place a relatively small quantity of oil within the base portion of the large gear 5 so that in the rotation of the small gear 13, the gear teeth will be thoroughly lubricated, as well as the crank shaft and wrist 35 pin connection for the reciprocating rod 16.

We have herein shown and described the preferred construction and relative arrange-

ment of the several parts of the device, but it will of course be understood that the same are susceptible of considerable modification 50 and we, therefore, reserve the privilege of adopting all such legitimate changes as may be fairly embodied within the spirit and scope of the invention as claimed.

We claim:—

1. A device of the character described comprising a fixed internally toothed gear, said gear having an annular track at one end of the gear teeth, side plates closing the opposite sides of the gear, a shaft rotatably supported by one of said side plates at the axial center of the gear, a crank arm fixed upon said shaft, a relatively small gear wheel rotatably supported by the crank arm and meshing with the teeth of the internal 65 gear and having an annular flange engaged upon said track, a wrist pin fixed to the small gear, and a rectilinearly movable reciprocating rod connected to said wrist pin.

2. A device of the character described 70 comprising a fixed internally toothed gear, said gear having an annular internal track at one end of the gear teeth, side plates closing the opposite sides of the gear, a shaft rotatably supported by the side plate remote 75 from the annular track of the gear, and at the axial center of said gear, a crank arm fixed upon said shaft, a relatively small gear wheel rotatably supported by the crank arm and meshing with the teeth of the internal 80 gear and having an annular flange engaged upon said track, a wrist pin fixed to the small gear, and a rectilinearly movable reciprocating rod connected to said wrist pin.

In testimony whereof we hereunto affix our signatures in the presence of two witnesses.

WILLIAM B. BALDWIN.
JOHN CURTIN.
